ATTORNEY

UNITED STATES PATENT OFFICE.

JOHN STONE STONE, OF SAN DIEGO, CALIFORNIA, ASSIGNOR TO AMERICAN TELEPHONE AND TELEGRAPH COMPANY, A CORPORATION OF NEW YORK.

REACTANCE NEUTRALIZING NETWORK.

Original application filed November 30, 1920, Serial No. 427,392. Divided and this application filed May 27, 1926. Serial No. 112,117.

It is an object of my invention to provide a network comprising as a part thereof a given circuit element having reactance so that the network as a whole shall have zero 5 reactance over a certain desired frequency range.

This application is a division of my pending application, Serial No. 427,392, filed November 30, 1920, for a circuit for passing 10 or stopping a frequency band of alternating currents. In that case I have disclosed a network to be interposed between a source of electromotive force and apparatus connected in circuit therewith, this network being designed 15 to present an approximately uniform high or low impedance over a certain frequency range and an impedance of opposite character for frequencies outside that range.

In the design of such an interposed network 20 it is desirable that the device to which the current is to be supplied from the source shall have substantially zero reactance over the intended frequency range, and in that case I have disclosed a combination of apparatus to get such a zero reactance. This 25 combination forms the subject matter of the present divisional application.

Referring to the drawings, Figure 1 is a diagram illustrating one embodiment of 30 the invention here claimed; and Fig. 2 is a curve diagram illustrating the performance of the apparatus of Fig. 1.

Among the more important cases for 35 which it will be desired to neutralize the reactance, the latter will have one of the three forms, $L\omega$, $\frac{1}{C\omega}$ and $\alpha_0 RS$, where L stands for inductance, C for capacity, ω is the frequency multiplied by 2π , R is resistance and α_0 and S are the frequency function and selectance as defined in the following equations:

$$\alpha_0 = \frac{f^2 - f_0^2}{ff_0} \quad (1)$$

$$S = \sqrt{\frac{L}{CR^2}} \quad (2)$$

50 Both of these equations have reference to a

tuned circuit of series inductance L, capacity C, resistance R and resonant frequency f_0 .

Of the three forms of reactance mentioned above either of the first two may always be 55 reduced to the third form by supplementing it with proper circuit elements. When the reactance is of the first form, that is when it is a pure inductance reactance, the addition of a capacity reactance in series will produce the third form. Again, if the initial 60 reactance be of the second form, that is if it be a pure capacity reactance, the addition of an inductance reactance in series will produce the third form. And the third form 65 represented by $\alpha_0 RS$ taken in connection with equations 1 and 2 is seen to correspond to the reactance of a resonant circuit having the resonant frequency f_0 .

Having reduced the reactance of the circuit to this last mentioned form additional reactance is chosen and introduced in series so as to make the resonant frequency f_0 of the resulting resonant circuit correspond to the medial frequency of the band of frequencies over which the reactance is to be neutralized. The combination reached at this stage is represented by the inductance 70 and capacity 52 of Fig. 1. The initial reactance may be represented by a part of the 75 inductance 51 or by a part of the capacity 52, but as described above it has been supplemented by further reactance elements to make the combination of 51 and 52 in Fig. 1 having the desired resonant frequency f_0 . 80

In series with the combination 51, 52 and in parallel with each other are the three elements 53 an inductance, 54 a capacity and 55 a resistance. This resistance 55 is shown as the input impedance of a thermionic vacuum tube. For the present it may be thought of merely as a resistance of considerable magnitude, and the reason for showing a vacuum tube will become apparent later 90

The reactance of the combination 51, 52 95 is given by the ordinates of curve 1 of Fig. 2, and the reactance of the combination 53, 54, 55 of Fig. 1 is given by the curve 2 of Fig. 2. The abscissæ of these curves in Fig. 2 are values of the frequency function 100

α_0 and the ordinates of curve 1 are given by equation,

$$y = \alpha_0 \cdot RS \quad (3)$$

5 and the ordinates of the curve 2 are given by the equation,

$$y' = \frac{-\alpha_0 X_1}{G_1(1 + \alpha_0^2 X_1^2)} \quad (4)$$

10 In equation 4, G_1 stands for conductance, the reciprocal of the resistance R_1 for the element 55; and $X_1 = \sqrt{(C_1/L_1 G_1)^2}$ in which C_1 , L_1 , and G_1 are the capacity, inductance, and conductance, respectively, of the 15 branches 54, 53, and 55 of the loop circuit. In equation 4 when $\alpha_0^2 X_1^2$ is negligibly small compared to unity the expression reduces to

$$20 - \frac{\alpha_0 X_1}{G_1}$$

and this reactance will exactly neutralize the reactance of the series resonant circuit 25 51, 52 when $RS = X_1/G_1$.

25 For the purpose of a concrete illustration, let us assume that 0.04 is the largest quantity which we can regard as negligible in comparison with unity. Accordingly 30 $\alpha_0^2 X_1^2 = 0.04$ represents the limiting value of $\alpha_0^2 X_1^2$ in a single loop neutralizer, so that in this case we have $\Delta X_1 = 0.2$. Therefore in the case of the single loop neutralizer we have these conditions: $\Delta X_1 = 0.2$ and 35 $RS = \frac{X_1}{G_1}$, the latter equation reducing to

$$\sqrt{\frac{L}{C}} = \frac{1}{G_1^2} \sqrt{\frac{C_1}{L_1}}$$

40 where

$$X_1 = \sqrt{\frac{C_1}{L_1 G_1^2}}$$

45 and where C_1 , L_1 , and G_1 are the capacity, inductance and conductance, respectively, of the loop. The resistance of this loop throughout the band of width 2Δ will be substantially $\frac{1}{G_1}$.

50 Subject to the conditions stated above the resultant reactance of the whole combination shown in Fig. 1 is given by the curve 3 of Fig. 2 whose ordinates are obtained by 55 adding the ordinates of the curves 1 and 2.

Thus it will be seen in Fig. 2 that the whole combination is approximately of zero reactance for a certain range of frequencies in the neighborhood of the frequency corresponding to zero value for α_0 .

60 It is believed that the foregoing discussion of an example of the use of a band reactance neutralizer will sufficiently indicate its utility in various connections. To carry the particular example already discussed a little further; that is, to make it still more specific, the filament and grid of an audion have been indicated in Fig. 1. The most effective condition is that in which the conductance of this translating device is made 65 the conductance of a band reactance neutralizer which neutralizes the reactance $\alpha_0 \cdot RS$, of the resonant circuit with which the translating device is connected. This mode of connection is the most efficient possible. 70 The magnitude of the reactance of a loop is not affected by the algebraic sign of the conductance G_1 , so that the translating device may have a negative conductance in which case it becomes regenerative. 75

I claim:

1. In combination, a circuit, a device in said circuit having a considerable amount of reactance, a supplemental reactance to make the combination resonant to a desired 80 frequency, and in series with said combination a band reactance neutralizer comprising an inductance and a capacity and a resistance in parallel and adapted to neutralize the reactance of said combination at and near the said desired frequency.

2. In combination, a circuit, a device in said circuit intended to absorb energy, also another device in series in said circuit having a considerable amount of reactance, a 85 supplemental reactance to make the combination resonant to a desired frequency, and in series with said reactance combination a band reactance neutralizer comprising an inductance and a capacity in parallel with each other and also comprising said first mentioned device in parallel with said inductance and capacity and adapted to neutralize the reactance of said combination at and near the said desired frequency. 95

100 In testimony whereof, I have signed my name to this specification this 18th day of May, 1926.

JOHN STONE STONE,
